(57) **CLAIM**

I claim the ornamental design for a cable lock, as shown and described.

DESCRIPTION

FIG. 1 is a front perspective view from above of the cable lock in a locked configuration;

FIG. 2 is a front view of the cable lock of FIG. 1;

FIG. 3 is a rear view of the cable lock of FIG. 1;

FIG. 4 is a left side view of the cable lock of FIG. 1;

FIG. 5 is a right side view of the cable lock of FIG. 1;

FIG. 6 is a top view of the cable lock of FIG. 1;

FIG. 7 is a bottom view of the cable lock of FIG. 1;

FIG. 8 is a rear perspective view from above of the cable lock of FIG. 1;

FIG. 9 is a front perspective view from below of the cable lock of FIG. 1;

FIG. 10 is a front perspective view from above of the cable lock of FIG. 1 in an unlocked configuration;

FIG. 11 is a front view of the cable lock of FIG. 1 in an unlocked configuration; and,

FIG. 12 is a top view of the cable lock of FIG. 1 in an unlocked configuration.

Stipple shading is used to indicate a cable strand of a contrasting color to the unshaded cable strands.
